United States Patent

Des. 236,168
Patented July 29, 1975

236,168

BAKERY TRAY OR THE LIKE

Lewis T. Johnson, Bartlesville, Okla., assignor to Phillips
Petroleum Company, Bartlesville, Okla.

Filed July 19, 1973, Ser. No. 380,592

Term of patent 14 years

Int. Cl. D9—03

U.S. Cl. D87—1 R

FIG. 2

FIG. 3

FIG. 6

FIG. 7

FIG. 8

FIG. 9

FIG. 1 is a top perspective view of a bakery tray or the like showing my new design;

FIG. 2 is a top plan view;

FIG. 3 is a bottom plan view;

FIG. 4 is a side elevational view;

FIG. 5 is an end elevational view;

FIG. 6 is an enlarged sectional view taken on the line 6—6 of FIG. 2;

FIG. 7 is an enlarged sectional view taken on the line 7—7 of FIG. 2;

FIG. 8 is an enlarged sectional view taken on the line 8—8 of FIG. 2; and

FIG. 9 is an enlarged sectional view taken on the line 9—9 of FIG. 4.

I claim:

The ornamental design for a bakery tray or the like, as shown and described.
